UNITED STATES PATENT OFFICE

HENRY J. GAISMAN, OF NEW YORK, N. Y., ASSIGNOR, BY MESNE ASSIGNMENTS, TO
GILLETTE SAFETY RAZOR COMPANY, OF BOSTON, MASSACHUSETTS, A CORPORATION
OF DELAWARE

SAFETY RAZOR

Application filed December 10, 1929. Serial No. 413,108.

My invention relates to the class of safety razors in which a blade is clamped between a guard member and a blade backing member.

One of the objects of my invention is to provide a blade having apertures or openings so arranged as to increase its flexibility for bending in a blade holder, as compared to known types of blades, and in which the blade will cooperate with the clamping members in such a way that the blade will be retained in shaving relation to the guard member and will retain the backing member in proper relation to the cutting edges of the blade, the blade apertures being adapted to receive non-cylindrical or cylindrical studs.

Another object is to provide the backing member with projections to enter apertures within the body of the blade in such a way as to retain the said member in proper relation to the blade edges; the projections, and the apertures in the blade, being located relatively to studs on the guard member that retain the blade with relation to the guards of the latter member.

My invention comprises novel details of improvement that will be more fully hereinafter set forth and then pointed out in the claims.

Reference is to be had to the accompanying drawing, wherein

Fig. 1 is an edge view of my improved razor assembled for use; Fig. 2 is a section on line 2, 2 in Fig. 1; Fig. 3 is a plan view of the blade; Fig. 4 is a partly broken plan view of Fig. 1; Fig. 5 is a section on line 5, 5 in Fig. 4; Fig. 6 is a section on line 6, 6 in Fig. 4; Fig. 7 is a plan view of the guard member; Fig. 8 is an inverted plan view of the backing member; Fig. 9 is an inverted plan view of a modified backing member; Fig. 10 is a plan view of a modified guard member for the backing of Fig. 9; Fig. 11 is a plan view of another modified guard member, and Fig. 12 is an underside view of a modified backing member.

Similar numerals of reference indicate corresponding parts in the several views.

At 1 is a guard member having guards 1a, and at 2 is a backing member, between which members a blade 3 is adapted to be clamped for shaving. Suitable means may be pro-

vided for retaining the members 1 and 2 clamped against the blade. I have illustrated the backing member provided with a threaded stud 4 adapted to pass through a substantially central hole 5 in the blade and through a hole 6 in the guard member for engagement with a threaded recess 7 in a handle 8 for clamping the members 1 and 2 against the blade, in a well known way. On opposite sides of the hole 5 the blade is provided with spaced apertures 3a, 3a adapted to receive studs 9 that are carried by the member 1 in spaced relation, (Figs. 2 and 4). The blade is provided with slots 10 that communicate with the apertures 3a and with the hole 5, said slots extending longitudinally and substantially centrally of the blade, whereby flexibility of the blade is increased for bending in the holder. At 3b are transversely elongated portions of the apertures 3a in the blade, which in effect define an enlarged area of each aperture, some of said elongated portions communicating with the longitudinal slots 10, (Figs. 3 and 4). The apertures 3a have spaced oppositely disposed edges 3c, defining an area therebetween in which studs 9 or 9a are adapted to be received. The projecting edge portions 3c have spaced oppositely extending portions 3d adjacent to the elongated portions 3b of the apertures, the portions 3d being spaced apart to receive the studs. Studs 9 and the blade edges 3c are shown in non-cylindrical form. Said edges 3c are so arranged as also to receive and engage cylindrical studs therebetween. In Fig. 11 cylindrical studs 9a are shown on the guard member. The aforesaid studs serve to retain the blade on the guard member with the cutting edges in shaving relation to the guards 1a (Figs. 4 and 11). The blade hole or opening 5 is shown as non-cylindrical and the stud 4 has a non-cylindrical portion, at 4a, adapted to enter the corresponding non-cylindrical portion 5a of hole 5, to retain the member 2 in position on the blade. The studs 9 have extended portions 9b that enter aperture portions 3b, on the side toward hole 5, as shown in Fig. 4. In Fig. 10 the studs 9 have extended portions at 9c that are adapted to

enter portions 3b of the blade apertures 3a opposite to that shown in Fig. 4.

The backing member 2 is shown provided with projections 11, that are spaced apart, and are located on opposite sides of the stud 4, which projections are adapted to enter aperture portions 3b of the blade. As shown in Figs. 2 and 4, the aperture portions 3b of the blade and the projections 11 are of elongated shape and extend in their greater dimension in a direction transversely with respect to the cutting edges of the blade. In the form shown in Figs. 1 to 8 the projections 11 are so spaced as to enter the outermost portions 3b of the blade, but said projections may be placed nearer together so that they may enter the portions 3b that are nearer to the centre of the blade, as indicated in Fig. 9. The non-cylindrical portion 4a of stud 4 may cooperate with the non-cylindrical hole 5 of the blade, to retain the member 2 in shaving relation to the blade edges, with or without the use of the projections 11, according to the backing shown in Fig. 4. By omitting the non-cylindrical portion 4a of stud 4 the projections 11 will retain the member 2 in shaving relation to the blade edges.

In accordance with the construction described, the studs from the guard member, 30 by engaging the edge portions of the blade apertures 3a, retain the blade cutting edges in proper relation to the guards, both in a longitudinal and a lateral direction with respect to the blade, and the projections 11, 35 that enter apertures of the blade, as well as the non-cylindrical portions 4b of stud 4, that enters hole 5 of the blade, serve to retain the backing member in proper relation to the cutting edges of the blade. The aperture or slot-like portions 3b, that extend transversely of the blade, aid in increasing the flexibility of the blade in a transverse direction while also being adapted to receive elongated projections 11. The backing member 2 is shown grooved or hollow, at 2', whereby the studs 9 or 9a may have suitable height without interfering with the backing member. The guard member 1 is shown provided with openings 12 to receive the projections 50 11.

My improvements operate to retain the blade in shaving relation to the guards and to retain the backing in desired relation to the blade edges in a manner set forth in Letters Patent to me No. 1,633,739, issued June 28, 1927. The blade described is also adapted to receive non-cylindrical or cylindrical studs from a clamping member in a manner set forth in Letters Patent to me No. 60 1,658,435, issued February 7, 1928.

The studs 9, 9a and the projections 11 are adjacent within the area of the blade and are located symmetrically with respect to the longitudinal axis of the members 1 and 2, to enter the appropriate apertures of the blade,

whereby the blade may be fitted in various positions between the clamping members, and the cutting edges of the blade will be maintained in proper position with respect to the guards and the backing in either position of the blade. 70

The outermost transversely disposed aperture portions 3b of the blade are located adjacent to projecting end portions 3' of the blade that are beyond said portions 3b and are shorter than the width of the blade between its cutting edges, the ends of the portions 3' of the blade being defined by reduced portions 3'' of the blade at its ends. The width of the portions 3' of the blade at each end is substantially symmetrical between the extreme outer edge of said portion and the adjacent edge of the slot portion 3b, the uniformity in width of the portions 3' of the blade serving to permit the metal of said portions 3' to readily flex when clamped between the members 1 and 2. The backing member 2 is shown provided with lugs 14, near the corners of the blade, which project from said member in position to enter the spaces at the reduced portions 3'' of the blade, and oppose the ends of the blade portions 3', (Fig. 4). In case the blade should break at the end portions 3' when between the clamping members the lugs 14 will oppose the adjacent parts of the blade and prevent them from becoming displaced from between said members. 90 95

My improvements provide a safety razor and blade having advantageous features, 100 since the apertures 3a, 3b, the slots 10 and the hole 5 all communicate and permit the blade to bend in a transverse direction with flexibility of such a character as to resist cracking or breaking of the end portions of the blade, at 3', when clamped between the members 1 and 2. Since the studs locate and retain the blade with respect to the guards 105 1a and the blade also locates and retains the backing member 2, by means of the projections 11, in the proper position, the assembled parts always will be in the desired shaving relation. 110

Having now described my invention what I claim is:

1. A safety razor blade of substantially oblong contour provided with cutting edges along its longer sides, said blade having an elongated slot intermediate the cutting edges thereof terminating in transverse enlargements adjacent the ends of the blade, the end margins of the slot forming with the ends of the blade elongated flexing portions or hinges having at least the major portions thereof beyond the ends of the cutting edges of said blade. 120 125

2. In a safety razor blade according to claim 1, said hinges being flexible and resilient. 130

3. In a safety razor blade according to claim 1, said hinges being of uniform thickness and universally flexible.
4. In a safety razor blade according to claim 1, said cutting edges being bounded at their ends by recesses in the blade corners which limit the cutting edges to a length not exceeding that of the slot.
5. A safety razor blade of substantially oblong contour provided with cutting edges along its longer sides, said blade having an elongated slot intermediate the cutting edges thereof terminating in transverse enlargements adjacent the ends of the blade, said blade having projecting end portions narrower than the width of the blade between said cutting edges and the end margins of the slot forming with the blade-end portions elongated flexing portions or hinges having at least the major portions thereof beyond the ends of the cutting edges of said blade.
6. In a safety razor blade according to claim 5, said blade slot having a central transverse enlargement for receiving the clamping pin of a blade holder.
